DISPENSING CLOSURE FOR BOTTLES OR THE LIKE

Jose Sanchis, Irvington, N.J.

Application July 28, 1958, Serial No. 51,966

Term of patent 14 years

(Cl. D2—3)

Fig. 1

Fig. 2

The sides of the article opposite those shown in Figures 1 and 2 are the same as those illustrated.

I claim:

The ornamental design for a dispensing closure for bottles or the like, as shown and described.
